UNITED STATES PATENT OFFICE.

ARTHUR V. EGINTON, OF MERIDEN, CONNECTICUT, ASSIGNOR TO INTERNATIONAL CASKET HARDWARE CO., OF MERIDEN, CONNECTICUT, A CORPORATION OF CONNECTICUT.

DESIGN FOR A BURIAL-CASKET HANDLE.

45,451.

Specification for Design.

Patented Mar. 24, 1914.

Application filed February 12, 1914. Serial No. 818,416. Term of patent 7 years.

To all whom it may concern:

Be it known that I, ARTHUR V. EGINTON, a citizen of the United States, residing in the city of Meriden, county of New Haven, and State of Connecticut, have invented a new, original, and ornamental Design for a Burial-Casket Handle, of which the following is a specification, reference being had to the accompanying drawing, forming part thereof.

My new design consists in an ornamentation made to represent embossed plush.

The figure is a perspective view of a burial casket handle showing my new design.

I claim:

The ornamental design for a burial casket handle, as shown.

ARTHUR V. EGINTON.
